(57) **CLAIM**

The ornamental design for a cosmetic container, as shown and described.

DESCRIPTION

FIG. 1 is a top, front perspective view of my design comprising a cosmetic container, wherein the cap is opaque and the base is translucent;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a top, front perspective view of a second embodiment of my design comprising a cosmetic container, with the only difference from the first embodiment being that the base is transparent in the second embodiment. Otherwise, the overall shape of the container in the second embodiment is the same as that shown in FIGS. 2–6.

The bottom surface of the cosmetic container is translucent in FIGS. 1–6 and transparent in FIG. 7. All other surface(s) or portion(s) of my design not shown in the figures or otherwise described in the specification form no part of the claimed design.
